CLAIM

The ornamental design for a connector, as shown and described.

DESCRIPTION

FIG. 1 is a perspective view;

FIG. 2 is a top plan view;

FIG. 3 is a bottom plan view;

FIG. 4 is a left side view;

FIG. 5 is a right side view;

FIG. 6 is a front view;

FIG. 7 is a back view;

FIG. 8 is a perspective view of the connector in a rotated position;

FIG. 9 is a top plan view of the connector in a rotated position;

FIG. 10 is a bottom plan view of the connector in a rotated position;

FIG. 11 is a left side view of the connector in a rotated position;

FIG. 12 is a right side view of the connector in a rotated position;

FIG. 13 is a front view of the connector in a rotated position;

FIG. 14 is a back view of the connector in a rotated position; and,

FIG. 15 is a bottom perspective view of the connector in a rotated position.

The Dash-Dash broken lines illustrate environmental features or portions of the connector that form no part of the claimed design. The Dash-Dot broken lines illustrate the boundary of the claim that form no part of the claimed design.

1 Claim, 9 Drawing Sheets
